PERMANENT WAVING DEVICE

Armand E. Lackenbach, New York, N. Y.

Application August 25, 1932, Serial No. 630,332

35 Claims. (Cl. 132—36.2)

The invention relates to devices used in the art of imparting a wave or curl to the human hair, which art is commonly referred to as permanent waving. More particularly, the invention relates to a pad or similar device employed in that branch of the art of permanent waving in which the permanent waving is accomplished without the use of electricity, heating elements, and cumbersome associated apparatus.

10 In the art of permanent waving, without the use of electricity, the heat necessary for imparting the wave or curl to the human hair is obtained by means of a device, generally a pad, which comprises an envelope attached to a backing 15 of aluminum foil, the envelope containing a mixture of certain chemicals, the main ingredient of such mixture being calcium oxide, the envelope containing the mixture being perforated by the operator just prior to applying the 20 same to the hair, a strip of flannel or felt being saturated with a solution and then placed over the surface of the envelope which has been perforated so that the moisture from the flannel or 25 felt strip may seep through the perforations and come into contact with the chemical mixture resulting in the development of an amount of heat and of a degree of temperature sufficient to actually boil the water and to impart a permanent wave to the hair which has been curled upon 30 a rod and enveloped by the pad.

The disadvantages of a device such as just described are manifold. In the first place, the time and gradation of the heat development, which may be described as the "heat control" 35 of the operation, are not determinable with sufficient certainty to insure the attainment of uniform and satisfactory results. The sudden development of heat when the moisture from the flannel or felt strip comes into contact with the 40 chemical mixture, and the attainment of the maximum degree of temperature within an extremely short period of time have the disadvantage that before even an expert operator can apply the hair to be waved properly to the pad and 45 position the latter correctly on the head, the pad becomes too hot for the operator to handle. A further disadvantage of such sudden and maximum development of heat is that for a period of a few minutes at the very beginning of the 50 permanent waving operation, the hair is brought from a normal temperature to an excessive baking temperature resulting in a drying of the hair brought about by such baking as distinguished from a gradual heating of the hair so that hair 55 permanently waved as just described will lose its

softness and will be characterized by a dryness which is detrimental to the life, lustre, and good appearance of the hair.

A further disadvantage of the use of the type of device above described is that the operator just prior to the application of the pad to the hair to be waved, must use a perforating tool in order to perforate the envelope containing the chemical mixture. If such perforation is accomplished any considerable period of time prior 10 to the carrying out of the permanent waving operation, the efficacy of the chemical mixture in developing the required amount and degree of heat is diminished by reason of the absorption thereby of the moisture in the atmosphere which 15 is enabled to reach such chemical mixture through the perforations. For best results it is therefore necessary to make the perforations in the envelope containing the chemical mixture just prior to the actual permanent waving operation. Inasmuch as the permanent waving operation of a head of hair requires between 24 and 48 pads, the operator is considerably fatigued by the necessity of perforating the envelopes individually just prior to the permanent 20 waving operation so that the operation of curling the hair on a rod and then enveloping such rod by means of the pad is a task which even 25 the most expert operator will find extremely tiring.

30 A still further disadvantage of the pads for permanent waving without electricity as now used is that there is no means of definitely controlling the speed of heat development, the time at which the heat begins to develop, and the time 35 during which the heat developed has been entirely dissipated so that sufficient cooling of the pad can take place for the operator to remove such pad after the completion of the permanent waving operation.

40 In accordance with my invention I overcome all of these disadvantages and more particularly provide a pad which eliminates the necessity of perforating the envelope containing the chemical mixture, makes possible the determination of the 45 precise moment at which the heat is permitted to develop, and permits a perfect control of the development of the heat after the beginning of such heat development.

Particular embodiments of my invention are 50 illustrated in the accompanying drawings, in which Fig. 1 is a plan view of a pad in accordance with my invention; Fig. 2 is a section on the line 2—2 of Fig. 1; Fig. 3 is a section on the line 3—3 of Fig. 1; Fig. 4 is a plan view of a modified form 55

of pad in accordance with my invention; Fig. 5 is a section on the line 5—5 of Fig. 4; Fig. 6 is a section on the line 6—6 of Fig. 4; Fig. 7 shows the pad of Fig. 4 in its rolled up condition in which it may be marketed to receive the curler rod and hair wound thereon; Fig. 8 is a plan view of still another embodiment of my invention; Fig. 9 is a section on the line 9—9 of Fig. 8; Fig. 10 shows the pad of Fig. 8 in the form of a roll; and Fig. 11 is a section similar to Fig. 9 with the pad of Fig. 8 slightly modified.

Referring more particularly to the drawings, the embodiment of my invention illustrated in Figs. 1 to 3 represents what at the present time I consider the preferred form of my novel pad. In said figures, 12 represents an envelope of soft pliable metal material, for instance, aluminum, attached by any suitable adhesive to a backing foil 13 of similar soft pliable material. The outer face 14 of the envelope 12 is provided with a plurality of preferably uniformly distributed apertures 15 of a size and number determined by the time element desired for the commencement of the heat development as hereinafter more fully described. I have found that for best results the apertures 15 should be approximately one-sixteenth of an inch in diameter and approximately 128 to the square inch of surface area. Of course, the size and distribution of the apertures over the surface of the envelope face may be varied and the dimensions herein given should be regarded as merely approximate.

The envelope 12 is filled with a mixture of chemicals 16 separated from the apertured face 14 by a sheet or film 17 of a readily soluble material, such as gelatin. A sheet or strip 18 of flannel, felt, or similar absorbent textile material is attached, in any suitable manner, as by an adhesive composition, at one end of the envelope 12. A sheet of parchment 19 or other oil-treated paper forms a backing for the entire envelope and metal foil structure. The parchment sheet 19, as shown, extends outwardly from the upper edge of the envelope and somewhat to the left of the side of the envelope.

In applying the pad just described, the strand of hair to which a wave is to be imparted is curled on a curler rod in the well-known manner, the rod, with the hair curled thereon, being placed longitudinally along the bottom edge of the envelope after the flannel or felt strip 18 has been moistened with the usual permanent waving solution and folded over the perforated face of the envelope so as to substantially cover the perforations therein; the envelope is then rolled over such curler rod in the well-known manner, the rolled pad being sealed with a clip below the end of the curled rod and the extension of the parchment and metal foil at the right of the envelope being twisted in the manner well known to those skilled in the art of permanent waving. The pad, having thus been applied, will commence its action on the hair, the solution from the textile sheet seeping into contact with the film or sheet of gelatin, dissolving the same, and thereafter contacting with the chemical mixture within the envelope and generating the amount and degree of heat sufficient to raise the water to boiling point and impart a permanent wave to the hair wound upon the curler rod.

The modified form of my invention, illustrated in Figs. 4 to 7, eliminates the use of the metallic backing as well as of the parchment. In such figures, 20 represents an envelope of soft pliable metal material, for instance, aluminum, having

an inner lining 21 of gelatin, formed simultaneously with the metallic envelope, containing the chemical mixture 22, as appears clearly from the seam 22', the outer face of the envelope 20 being provided with a plurality of preferably evenly distributed apertures 23. A strip of felt or flannel 24 is secured to the perforated face of the envelope as by folding the edges thereof inwardly along the ends of the envelope to form the beads 25, 25 (Fig. 6). The manner of applying this modified form of my invention to the curler rod upon which the hair to be waved is wound is similar to that described hereinabove with respect to the preferred form of Figs. 1 to 3, the pad being wound upon the curler. In Fig. 7, I have illustrated my modified form of pad wound into a roll for marketing in such form so that all that is necessary in its use is to place the curler, with the hair wound thereon, within the roll. This form of my invention is particularly adapted for use with a certain type of hair waving device eliminating the necessity of sealing the ends of the rolled pad with a clip on one end and by twisting the foil at the other end.

In the still further modified form of my novel pad, illustrated in Figs. 8 to 10 of the drawings, a backing sheet 26 of soft pliable metal material, for instance aluminum, and having an extension 27 on one side thereof, is used for mounting the envelope 28 of similar soft pliable metal material. The envelope in this case is also provided with preferably uniformly distributed apertures 29 on the exposed face thereof, the apertures being shown as of much larger diameter than those of the two previously described embodiments. A sheet 30 of soluble material, for instance, gelatin, is placed between the outer perforated face of the envelope and the mixture of chemicals 31. In order to prevent the chemicals from being dislodged from the envelope when the film of gelatin has been dissolved in the course of the permanent waving operation, I place a sheet 32 of gauze or any similar material between the film of gelatin and the perforated face of the envelope. The chemical mixture, after its function of heat development has been performed, becomes a somewhat caked mass, so that the gauze will prevent any portion thereof from being spilled through the apertures of the envelope when the pad is being removed. The strip of absorbent textile material 33, for instance flannel or felt, is secured to the upper edge of the metal backing 26 as by an adhesive or by stitching 34 and is adapted to be saturated with permanent waving solution and then folded over the perforated envelope. When the strip 33 has been folded over the perforated face of the envelope, the extension 27 of the backing material 26 is folded over so as to overly the textile strip, resulting in a compact pad.

The pad of Figs. 8 and 9 may be rolled into the form shown in Fig. 10 to be sold in such form into which the curler rod having the hair wound thereon may be inserted.

The pad illustrated in Fig. 11 differs from that of Figs. 8 to 10 only in that instead of the film of soluble material being provided only between the chemical mixture and the gauze sheet, such film or sheet surrounds the entire charge of chemicals and may therefore be said to line the entire inner surface of the metal envelope.

The operation of the device, having regard to the slight modifications present in the various forms illustrated, is as follows: The usual rod, upon which the hair to be waved is wound, is to

be applied to the pad in the usual manner, i. e. by placing the rod with the hair wound thereon upon the face of the pad parallel to its lower edge and winding the pad upon the rod. The usual clip and felt disc are placed on the hair immediately adjacent the scalp to protect the scalp. The opposite or free end of the pad is secured in a tubular condition by twisting it in the usual well-known manner.

10 Prior to the application of the rod having the hair wound thereon to my pad the flannel or felt strip is dipped into a permanent waving solution so that it is completely saturated thereby and it is then flipped over the envelope containing the 15 chemical mixture, the strip entirely covering the surface of the envelope provided with the apertures. In the modification in which the textile strip is permanently attached to the envelope, the entire envelope is dipped into the permanent 20 waving solution. The pad having then been wound about the rod, the moisture from the flannel or felt strip, coming into contact with the gelatin covering the apertures of the envelope will dissolve the gelatin in a certain predetermined 25 period of time, determinable by the thickness of the gelatin film, by the size and number of apertures, and also by the thickness of the flannel or felt strip by which thickness the amount of moisture required to saturate the strip is determined. Thus, the period of time during which the water will dissolve the gelatin film or sheet and is permitted to contact with the chemical mixture is a function of the thickness of the gelatin film, the size and number of apertures, and 30 the amount of solution acting upon such film to dissolve the same as determined by the saturation of the flannel or felt strip.

As the period during which the gelatin is to be completely dissolved so that the moisture from the flannel or felt strip can reach the chemical mixture is dependent upon the three elements just mentioned, it will be readily understood that the exact moment at which heat is to be developed can be readily controlled.

45 It is my present theory, to which, however, I desire not to be restricted as explaining the process taking place, that as the gelatin begins to dissolve, a certain area of the aperture covered by the film of gelatin will first be eaten away or dissolved so that only a small perforated area is available at the beginning of the period of dissolution of the gelatin for the moisture to enter within the envelope and commence its action on the chemical mixture. As the film of gelatin is 50 further dissolved more and more solution is enabled to seep through the enlarging aperture so that a greater amount of moisture is coming continually in contact with the chemical mixture. By reason of this condition, actual heat is not 55 developed until sufficient time has elapsed to enable the operator to complete the necessary steps of preparing the pad and the hair for the permanent waving. Furthermore, once the heat begins to develop, the development takes place gradually 60 until a maximum degree of temperature is attained, which maximum degree of temperature, higher than the boiling point of water, is maintained for a sufficient length of time to complete the waving of the hair. All of these time factors 65 are thus readily controllable by means of my novel construction, the period during which the heat is developed being easily controllable by the thickness of film, the amount and nature of the chemical mixture contained in the envelope, and 70 the size and number of the apertures. Once the

maximum degree of temperature has been reached and has been retained for a sufficient length of time to effect the permanent waving, the depletion of heat so as to cool the envelope is enhanced by the presence of the apertures in one 5 face of the envelope, through which the heat will more readily escape than if the entire envelope were made of material, for instance, aluminum foil, without any apertures.

While I have illustrated in the accompanying 10 drawings a sheet of gelatin as being applied to the inner surface of the perforated face of the envelope, it is obvious that it is possible to apply a thin layer of gelatin either to the outer or inner surface of the perforated face of the 15 envelope by various means. For instance, the gelatin may be dissolved and a solution thereof, for instance, with an admixture of glycerine, may be applied to the surface by means of a brush, the thickness of the layer being determinable by the consistency of the dissolved gelatin or of gelatin and glycerine. I have also found it expedient, if a solution of gelatin or of gelatin and glycerine of suitable consistency is prepared, to dip the perforated face of the envelope 20 into such solution so that the perforations will be closed by a thin film of the gelatin or gelatin and glycerine. Dipping the entire aluminum foil into a solution of gelatin also has the advantage of closing up the pores of such 25 foil, so that it is not necessary to pack the pad in air-tight containers when shipping the same. Various other methods of applying the film of gelatin and glycerine or gelatin alone to the perforated surface of the envelope will occur to those skilled in the art and I wish it to be understood that I do not wish my invention to be limited in any manner to a specific method of applying the film of gelatin to the perforated 30 surface of the envelope or to the use of a sheet of gelatin either on the inner or on the outer surface of the perforated face of the envelope.

While I have described my invention as embodying a sheet or thin film of gelatin, it is obvious that any readily soluble substance of similar 45 nature can be substituted for the gelatin. I therefore desire it to be understood that I do not restrict myself to the use of gelatin or any other particular preparation. Any material of suitable characteristics, particularly with respect 50 to solubility in solutions of the type used in permanent waving can be substituted for the gelatin film or layer.

The mixture of chemicals within the envelope may be any suitable mixture, the major ingredient 55 of which is a chemical which, upon contact with water, will develop an appreciable amount of heat. I have found that a mixture containing approximately 75% of calcium oxide, 10% of ammonium sulfate, and 12% of starch, 60 gives satisfactory results. Of course, any other oxide, the chemical equivalent of the calcium oxide, for instance, strontium and barium oxides, may be substituted for the calcium oxide.

While I have illustrated and described specific 65 embodiments of my invention, I wish it to be understood that such embodiments are illustrative only and that any alteration from the specific forms shown or any departure from or rearrangement of the elements thereof, within the 70 scope of the appended claims, is within the spirit of my invention.

I claim:

1. A pad for permanent waving without the use of electricity comprising an envelope of soft 75

- pliable metal material having a plurality of apertures in at least one face thereof and containing a mixture of chemicals, and a film of soluble material over said perforated face.
5. 2. A pad for permanent waving without the use of electricity comprising an envelope of soft pliable metal material having a plurality of apertures in at least one face thereof and containing a mixture of chemicals, and a sheet of soluble material in contact with the perforated face of said envelope.
10. 3. A pad for permanent waving without the use of electricity comprising an envelope of soft pliable metal material having a plurality of apertures in at least one face thereof and containing a mixture of chemicals, a film of soluble material over said perforated face, and a sheet of an absorbent textile material adapted to be applied to said perforated face.
15. 4. A pad for permanent waving without the use of electricity comprising an envelope of soft pliable metal material having a plurality of apertures in at least one face thereof and containing a mixture of chemicals, and a film of gelatin filling said apertures.
20. 5. A pad for permanent waving without the use of electricity comprising an envelope of soft pliable metal material having a plurality of apertures in at least one face thereof and containing a mixture of chemicals, and a sheet of gelatin over said apertures.
25. 6. A pad for permanent waving without the use of electricity comprising an envelope of soft pliable metal material having a plurality of apertures in at least one face thereof and containing a mixture of chemicals, a sheet of gelatin over said perforated face, and a sheet of an absorbent textile material adapted to be applied to said perforated face.
30. 7. A pad for permanent waving without the use of electricity comprising an envelope of soft pliable metal material having a plurality of apertures in at least one face thereof and containing a mixture of chemicals, and a film of water soluble material filling the apertures in said envelope.
35. 8. A pad for permanent waving hair comprising an envelope of soft pliable metal material having a plurality of apertures uniformly distributed throughout one face thereof, a mixture of chemicals within said envelope which, upon moisture coming in contact therewith, develops an amount of heat sufficient to raise water to boiling temperature, a film of soluble material over said apertures, and a textile sheet over the perforated face of said envelope.
40. 9. A pad for permanent waving hair comprising an envelope of soft pliable metal material having a plurality of apertures uniformly distributed throughout one face thereof, a mixture of chemicals within said envelope which, upon moisture coming in contact therewith, develops an amount of heat sufficient to raise water to boiling temperature, a sheet of gelatin over said apertures, and an absorbent textile sheet over the perforated face of said envelope.
45. 10. A pad for permanent waving hair comprising a backing of soft pliable metal material secured to a sheet of parchment, an envelope of soft pliable metal material having a plurality of apertures in one face thereof and secured to said backing sheet, a mixture of chemicals within said envelope, a sheet of a readily soluble material lining the inner surfaces of said envelope, and a sheet of an absorbent textile material
50. secured at one end of the envelope and adapted to be folded over the apertured face of said envelope.
55. 11. A pad for permanent waving hair comprising a backing of soft pliable metal material secured to a sheet of parchment, an envelope of soft pliable metal material having a plurality of apertures in one face thereof and secured to said backing sheet, a mixture of chemicals within said envelope, a sheet of gelatin lining the inner surfaces of said envelope, and a sheet of an absorbent textile material secured at one end of the envelope and adapted to be folded over the apertured face of said envelope.
60. 12. A pad for permanent waving hair comprising an envelope of soft pliable metal material having a plurality of apertures uniformly distributed throughout one face thereof, a mixture of chemicals within said envelope which, upon moisture coming in contact therewith, develops an amount of heat sufficient to raise water to boiling temperature, a sheet of readily soluble material lining the inner surface of the perforated face, and an absorbent textile sheet over the perforated face of said envelope.
65. 13. A pad for permanent waving hair comprising an envelope of soft pliable metal material having a plurality of apertures uniformly distributed throughout one face thereof, a mixture of chemicals within said envelope which, upon moisture coming in contact therewith, develops an amount of heat sufficient to raise water to boiling temperature, a sheet of gelatin over said apertures lining the inner surface of the perforated face, and an absorbent textile sheet over the perforated face of said envelope.
70. 14. A pad for permanent waving hair comprising an envelope of soft pliable metal material having a plurality of apertures throughout at least one face thereof, a mixture of chemicals within said envelope, a sheet of a readily soluble material lining the inner surface of said envelope, and a textile sheet secured at the two ends of the envelope so as to overlie the perforated face thereof.
75. 15. A pad for permanent waving hair comprising an envelope of soft pliable metal material having a plurality of apertures throughout at least one face thereof, a mixture of chemicals within said envelope, a sheet of gelatin lining the inner surface of said envelope, and a textile sheet secured at the two ends of the envelope so as to overlie the perforated face thereof.
80. 16. A pad for permanent waving hair as claimed in claim 14 formed into a roll.
85. 17. A pad for permanent waving hair comprising a backing sheet of soft pliable metal material, an envelope of soft pliable metal material having a plurality of apertures in one face thereof, a mixture of chemicals within said envelope, a sheet of a readily soluble material lining the inner surface of said apertured face, a sheet of absorbent textile material secured to said backing sheet and adapted to be folded over said perforated face of the envelope, and an extension on said backing sheet adapted to be folded over the sheet of absorbent textile material when the same has been folded over the apertured face of the envelope.
90. 18. A pad for permanent waving hair comprising a backing sheet of soft pliable metal material, an envelope of soft pliable metal material having a plurality of apertures in one face thereof, a mixture of chemicals within said envelope, a sheet of gelatin lining the inner surface of said aper-

- 5 tured face, a sheet of flannel material secured to said backing sheet and adapted to be folded over said perforated face of the envelope, and an extension on said backing sheet adapted to be folded over the sheet of flannel when the same has been folded over the apertured face of the envelope.
- 10 19. A pad for permanent waving hair as claimed in claim 17 in which the film of readily soluble material fills the apertures in the envelope.
- 15 20. A pad for permanent waving hair as claimed in claim 17 formed into a roll adapted to receive a curler rod having the hair to be waved wound thereon.
- 20 21. In an appliance for heat-treating hair, the combination, with a heating unit including an exothermic material and a sealed water-soluble container containing said material, of a water-insoluble means to isolate from the hair the substance of said unit when the container is dissolved.
- 25 22. An appliance for heat-treating hair comprising, with a heating unit including an exothermic material and a sealed water-soluble envelope containing said material, of a water-insoluble water-permeable envelope containing the first envelope, said envelopes being flat and flexible.
- 30 23. An appliance for heat-treating hair comprising, with a heating unit including an exothermic material and a sealed water-soluble container containing said material, of a water-insoluble water permeable container containing the first container and a water-absorbing material arranged exterior of and in contact with the second container and adapted to be interposed between it and the hair.
- 35 24. An appliance for heat treating hair comprising, with a heating unit including an exothermic material and a sealed container containing said material and having a portion thereof water-soluble, of means, water-permeable and substantially water-insoluble, to isolate the substance of said unit from the hair upon dissolving of said portion.
- 40 25. An appliance for heat treating hair comprising, with a heating unit including an exothermic material and a sealed container containing said material and having a portion thereof water-soluble, of means, water-absorbent and substantially water-insoluble, arranged to separate the substance of said unit from the hair upon dissolving of said portion.
- 45 26. In a hair waving pad, an exothermic material containing envelope of non-soluble material having a perforated face, and a sheet of soluble material for sealing said perforations.
- 50 27. In a hair waving pad, an exothermic material containing envelope of foil having a per-
- forated face, and a gelatine sheet for sealing said perforations.
- 55 28. In a hair waving pad, an exothermic material containing envelope of insoluble material having a perforated face, and a sheet of soluble material located within the envelope for sealing said perforations.
- 60 29. In a hair waving pad, an exothermic material containing envelope of foil and having a perforated face, and a gelatine sheet located with- 10 in the envelope for sealing said perforations.
- 65 30. A hair waving pad comprising an outer wrapper, an exothermic material containing envelope of non-soluble material and having a perforated face, a soluble sheet for sealing the 15 perforations and an absorbent sheet adapted to be moistened and placed in contact with the soluble sheet.
- 70 31. A pad for permanent waving without the use of electricity comprising an envelope of soft 20 pliable metal material having a plurality of apertures in at least one face thereof and containing an exothermic material, and a film of gelatine filling said apertures.
- 75 32. A pad for permanent waving without the use of electricity comprising an envelope of soft pliable metal material having a plurality of apertures in at least one face thereof and containing an exothermic material, and a film of water soluble material filling the apertures in said envelope. 30
- 80 33. A pad for permanent waving without the use of electricity comprising an envelope of soft pliable metal material having a plurality of apertures in at least one face thereof and containing an exothermic material, and means for covering 35 said apertures adapted to be removed by the user at the time and locus of use of said pad.
- 85 34. A pad for permanent waving without the use of electricity comprising an envelope of soft pliable metal material having a plurality of aper- 40 tures in at least one face thereof and containing an exothermic material, and a layer of material covering said apertures adapted to be disintegrated, from the metal material having the apertures in the face thereof, at the locus of use of said 45 pad.
- 90 35. A pad for permanent waving without the use of electricity comprising an envelope of soft pliable metal material having a plurality of apertures in at least one face thereof and containing 50 a mixture of exothermic chemicals, and a layer of material in contact with the perforated face of said envelope adapted to be disintegrated from the metal material having the apertures in the face thereof immediately preceding the exothermic re- 55 action of the chemicals.

ARMAND E. LACKENBACH.
